United States Patent Office.

E. HERBSTER, OF CHICAGO, ILLINOIS, ASSIGNOR TO HIMSELF, T. TRIPP,
AND E. F. BROWN, OF SAME PLACE.

Letters Patent No. 70,714, dated November 12, 1867.

IMPROVED SASH-FASTENER.

The Schedule referred to in these Letters Patent and making part of the same.

TO ALL WHOM IT MAY CONCERN:

Be it known that I, E. HERBSTER, of Chicago, in the county of Cook, in the State of Illinois, have invented an Improved Sash-Fastener; and do hereby declare that the following is a full and exact description thereof, reference being had to the accompanying drawings, and to the letters of reference marked thereon, making a part of this specification, in which—

Figure 1 is an elevation of my sash-fastener with the face removed.

Figure 2, a transverse sectional elevation of the same, taken through the line X X.

Figure 3, a perspective representation of the pin which locks the cog-wheel.

The nature of my invention relates to that class of fasteners or locks which have springs and cog-wheels for balancing the sash; and the peculiar arrangement, which I consider new, consists in making a series of holes in the main cog-wheel, and arranging a pin to enter either of said holes, and thereby lock the sash at any required point; and in the use of a cylinder or sleeve for the support of the pin, and a coil spring arranged with notches and slots for the purpose of holding the pin out of the holes in the wheel when the sash is to be run up or down; and further, in the use of a key arranged to pass through the casing and into a pinion for the convenience of winding the spring up to such a tension as is necessary to balance the sash.

In order to give a correct understanding of my invention, I have marked corresponding parts with similar letters, and will now give a detailed description.

A represents the case of a common sash-fastener fitted into a frame, shown by the broken line B, fig. 1. The broken line J represents a sash, and I the rack attached to the same for the purpose of causing said sash to be operated by means of cog-wheel D and spring C. The wheel D is made with a series of holes, b b, &c., in its face for the purpose of receiving a pin, E, which is arranged to have a reciprocating motion in a sleeve, F, and press against the surface of wheel D, preparatory to entering the holes b, by means of a coil spring, k, fitted to the inside of sleeve F, and made to press against a stop, f, put through pin E, as seen at fig. 2. The sleeve F, as shown at fig. 3, has a slot, h, made parallel with pin E, and a slot, n, made at right angles to h for the purpose of allowing stop f to pass through slot h, when pin E is to be drawn out of holes b, and be turned so as to lock in the short slot n, and thus be held in place during the time the sash J is being raised or lowered.

This arrangement is very simple, yet an effectual means for fastening sash, and as the knob P is made to project inside of the casing, no difficulty need be experienced, by persons of ordinary capacity, in operating the device. A pinion, G, is made to mesh in the cogs of wheel D, and has a square opening, S, for receiving the winding-key T put through the same plate U, which supports the pin E, and used to give the required tension to spring C for balancing a sash. This key can be readily removed when not in use, and when necessary, in order to secure cheapness, may be arranged to operate the shaft H of wheel D directly, in which case the pinion G need not be used.

Having thus fully described my device, what I claim, and desire to secure by Letters Patent, is—

1. The combination of wheel D, having holes b b, &c., with pin E, arranged to operate in sleeve F, having slots h and n, for the purpose of locking sash, substantially as herein set forth.
2. The combination of wheel D, spring C, pin E, sleeve F, and key T, arranged to wind said spring up, and to fasten sash, substantially as and for the purpose set forth.

EW. HERBSTER.
